APPARATUS FOR FORMING SAND MOLDS

3 Sheets-Sheet 2

Fig. 2.

The drawing illustrates a top-down view of a mechanical assembly. At the top, a circular component with a multi-layered, gear-like or labyrinthine internal structure is shown. Below this, a base structure is depicted with several labeled parts: 16, 41, 41, 42, 44, 46, 48, 3, 2, 42, 44, 46, 48, 3, 4, 1, and 2. The base appears to be a rectangular frame with various cutouts and internal features. The number 1 is also present near the bottom center. The entire assembly is labeled "Inventor" at the bottom right.

UNITED STATES PATENT OFFICE.

JOHN T. STONEY, OF CLEVELAND, OHIO.

APPARATUS FOR FORMING SAND MOLDS.

Application filed December 15, 1924. Serial No. 755,864.

This invention relates to apparatus for forming the sand molds in accordance with the method disclosed in my co-pending application Serial No. 732,358, filed Aug. 16, 1924, and has for its object to facilitate the handling of the flasks in which the sand molds are formed so that the interval between successive mold forming operations may be shortened.

More specific objects of the invention are to provide means for quickly freeing the flask from the follower which rests upon the body of sand in the flask during the forming operation and to provide means for facilitating the placing of flasks upon the table prior to the mold forming operation and for facilitating the removal of the flasks after the mold forming operation.

With the above and other objects in view the invention may be said to comprise the apparatus as illustrated in the accompanying drawing hereinafter described and particularly set forth in the appended claims, together with such variations and modifications thereof as will be apparent to one skilled in the art to which the invention appertains.

Reference should be had to the accompanying drawings forming a part of this specification in which Fig. 1 is a central vertical section taken on line 1—1 of Fig. 2; Fig. 2 is a top plan view with the platen supporting arm broken away and the platen omitted to show the top of the table; Fig. 3 is a transverse vertical section taken on broken line 3—3 of Fig. 2.

Referring to the accompanying drawings, the flask supporting table 1 is provided with a hollow supporting pedestal 2 in which is mounted a vertical cylinder 3 which has a vibrating piston 4 which reciprocates vertically between the upper and lower heads 5 and 6 of the cylinder. The cylinder 3 is provided with an air supply pipe 7 through which air under pressure is admitted to the cylinder to operate the piston. The piston 4 and cylinder 3 are so constructed that when air under pressure is supplied to the cylinder the piston 4 is rapidly reciprocated to impart percussive impulses in rapid succession to the flask supporting table 1 as in my co-pending application above referred to.

Mounted in a central opening in the upper head 5 of the cylinder is a percussion member 8 against which the piston 4 strikes upon

each upward stroke. The percussion member 8 has a fluid tight fit in the head 5 and is provided with an enlarged head 9 which rests upon the top of the head 5 and bears against the lower ends of table supporting posts 10 which are rigidly connected to the supporting table 1. The outer edges of the table 1 rest upon the upper edges of the walls of the hollow supporting pedestal 2 and means are preferably provided for yieldingly holding the table 1 in engagement with its support. To this end the table is provided adjacent the edges thereof with downwardly extending pins 11 which have a sliding fit in vertically disposed bosses 12 formed upon the inside of the walls of the supporting pedestal 2 and the table is yieldingly held in engagement with the supporting pedestal by means of compression coil springs 13 which are interposed between the lower ends of the bosses 12 and nuts 14 upon the lower ends of the pins 11. In forming the sand molds, a flask containing the sand to which the mold is to be formed is placed upon the table 1 and the compacting of the sand in the flask is accomplished by admitting fluid pressure to the vibrating cylinder 3 which causes the piston 4 to reciprocate rapidly and to impart percussive impacts in rapid succession to the percussion member 8 and through the supporting posts 10 to the table 1. The vibrations due to these impacts are transmitted through the table 1 and the flask thereon to the sand within the flask. These rapidly succeeding impulses in an upward direction cause the sand to rapidly settle and form itself into a compact mass.

In order to cause the sand to be more uniformly compacted throughout the entire mold, a follower in the form of a platen resting upon the top of the sand in the flask is provided. The present invention provides a follower so mounted that it may be easily and quickly lifted out of flask engaging position and moved laterally to a position clear of the flask to facilitate removal of the flasks after the mold forming operations. For supporting the follower a hollow cylindrical standard 15 is mounted alongside the supporting pedestal 2 and rigidly connected thereto by a hollow connecting portion 16 so that the interior of the member 15 is in communication with the interior of the hollow pedestal 2 for a purpose which will be hereinafter described.

The follower is mounted for vertical movement upon the supporting member 15 and comprises a head 17 slidably supported upon the supporting member, an arm 18 rigid with and extending laterally from the head 17 and a platen 19 which is rigidly secured to the platen at the center thereof and adjustably secured within the outer end of the arm 18. The platen 19 is formed to fit within the flasks in which the sand molds are to be formed and the entire follower moves downwardly by gravity during the mold forming operation.

The head 17 is provided with a depending sleeve 20 which fits slidably over the cylindrical supporting member 15 and with an integral inner sleeve 21 which has a fluid tight sliding fit upon a cylindrical extension 22 of reduced diameter which is rigidly secured to the upper end of the supporting post 15. A vertical shaft 23 is secured within the cylindrical extension 22 and extends through the upper end of the head 17 and fluid tight connections between the shaft 23 and the interior of the cylindrical member 22 and between the shaft 23 and the upper end of the head 17 are made by suitable glands 24 and 25. The pressure for lifting the head 17 is admitted through an air pipe 26 which communicates with inlet and exhaust pipes controlled by suitable valves (not shown) so that the head may be raised or lowered. An air chamber 29 surrounds the shaft 23 within the cylindrical member 22 above the gland 24 and an air passage 29^a within the wall of the standard 15 communicates with this chamber. An air passage 30 extends from the air chamber 29 to the upper end of the cylindrical member 22 to admit pressure between the upper end thereof and the head 17 to elevate the head 17, the space between the upper end of the cylindrical member 22 and the head 17 forming a pressure chamber so that when air under pressure is admitted through the inlet pipe 26, the follower is lifted bodily.

Whenever the air pressure is released, the follower may move downwardly by gravity, the air pressure being employed merely to lift the follower out of flask engaging position to permit it to be moved clear of the flask. While the follower is in flask engaging position and during the downward movement of the platen in the flask it is desirable that the follower be held against lateral movement. To this end the lower portion of the inner sleeve 21 of the head is connected with the outer portion thereof by means of integral ribs 31 and secured to the underside of the ribs 31 is an annular plate 32 which is concentric with the pivotal axis of the head. A vertical pin 33 is rigidly secured to the base portion of the cylindrical extension 22 and fits in an opening in the plate 32. The pin 33 is of a length such that

it will hold the follower against lateral swinging movement until the platen has been moved to a height such that it wholly clears the flask whereupon the plate 32 will be freed from the pin 33 and the follower is free to swing laterally. After the follower has been swung laterally and the air pressure released, the plate 32 will rest upon the top of the pin 33 retaining the follower in elevated position. When another flask has been placed upon the table the follower may be swung back to position the platen over the flask in which position the opening in the plate 32 will register with the pin 33 permitting the follower to descend by gravity until the platen 19 rests upon the sand in the flask.

In order to facilitate the placing of the flasks upon the table and the removal of the flasks therefrom, means are provided for lifting the flask and supporting the same above the surface of the table. The flask lifting means is actuated by means of a vertically disposed fluid pressure cylinder within the lower portion of the hollow standard 15, the cylinder comprising telescopically connected inner and outer cylinders 34 and 35. The inner cylinder 34 is fixed to the base of the standard and the outer cylinder 35 has a sliding fit upon the cylinder 34, the cylinders 34 and 35 having closed heads at their upper ends forming a pressure chamber to which air under pressure may be admitted through an inlet pipe 36 which extends through the inner cylinder 34. When air under pressure is admitted through the pipe 36 the outer cylinder 35 is lifted and the upward movement of the outer cylinder is limited by means of a yielding bumper 37 which has a vertically extending stem 38 rigidly secured to the head of the cylinder 35 and a spring 39 interposed between the head 35 and a washer 38^a held in place on the stem by a nut 38^b at the upper end of the stem. The lower end of the shaft 23 is in the path of movement of the stem 38 and is provided with a recess 40 at its lower end which is large enough to receive the nut 38^b at the upper end of the stem. Upon upward movement of the cylinder 35 the nut 38^b enters the recess 40 and the lower end of the shaft 23 engages the washer 38^a compressing the spring 39 and gradually bringing the cylinder 35 to a stop, the spring 39 and washer 38^a providing a yielding abutment for limiting the movement of the cylinder 35. The flask lifting device is connected to the outer cylinder 35 and comprises a U-shaped frame 41, the base portion of which is rigidly secured to the cylinder 35 and the arms of which extend through the hollow portion 16 into the hollow pedestals 2 upon opposite sides of the vibrator cylinder 3. Rigidly attached to the arms of the frame 41 beneath the corners of the table

are outwardly extending angle brackets 42 which are detachably secured to the arms of the frame 41 by studs 43 which engage in suitable openings formed in the arms of the frame. The outwardly projecting flanges of the angle brackets 42 have rigidly secured thereto vertical pins 44 which extend upwardly and have a sliding fit within bosses 45 formed in the walls of the pedestal 2, 10 the upper ends of the pins 44 being movable through openings in the table 1. Each of the arms of the frame 41 has rigidly secured thereto a vertical guide pin 46 midway between the pin supporting brackets 42 and these guide pins have sliding engagement with bearing members 47 in the table supporting frame. Additional guide pins 48 have their lower ends slidably mounted in openings in the arms of the frame 41 alongside the guide pins 46 and these pins are supported by nuts 48^a which rest upon the top of the arms, the pins 48 being guided in bearing members 49 in the fixed frame the upper ends of the guide pins 48 being connected by a cross bar 50 extending across the top of the vibrator cylinder 3. When air is admitted through the inlet pipe 36 to the chamber between the inner and outer cylinders 34 and 35, the outer cylinder 35 together with the frame 41 and the flask lifting pins 44 are elevated as a unit, the extent of vertical movement being limited by the engagement of the yielding buffer washer 38^a with the lower end of the shaft 23. 35 When the air pressure is released from the cylinder, the outer cylinder 35 drops by gravity and the lower edge thereof rests upon the base of the supporting standard 15 and in this position the upper ends of the flask lifting pins 44 are substantially flush with the top surface of the flask supporting table so that the flask rests directly upon the flat table. After the mold has been formed in the flask and the follower has been moved to a position clear of the flask pressure is admitted to the inlet pipe 36 to the pressure chamber between the cylinders 34 and 35 causing the cylinder 35 and with it the frame 41 and pins 44 to be elevated a short distance to lift the flask clear of the supporting table 1 so that the operator can conveniently lift the flask from the table and place another flask upon the projecting pins 44 whereupon the pressure will be released from the lifting cylinder and the flask will be lowered onto the table. The platen will then be swung to a position directly above the flask where the guide pin 33 will enter the opening in the annular plate 32 and the platen will be lowered by gravity into engagement with the sand in the flask whereupon the vibrator 3 will be operated to impart percussive impulses to the table to compact the sand in the flask.

Having described my invention, I claim—

1. In sand mold forming apparatus, the combination with a flask supporting member having means associated therewith for imparting percussive impulses thereto, of a gravity actuated follower comprising a platen 70 adapted to rest upon the sand in a flask, and means for lifting said platen and for supporting the same in a position clear of the flask.

2. In a sand mold forming apparatus, the combination with a flask supporting member having means associated therewith for imparting percussive impulses thereto, of a gravity actuated follower including a platen adapted to rest upon the sand in a flask, 80 and means for supporting said platen for bodily movements vertically and laterally to a position clear of a flask on the supporting member.

3. In a sand mold forming apparatus, the combination with a flask supporting member having means associated therewith for imparting percussive impulses thereto, of a gravity actuated follower comprising a head 90 mounted at one side of said supporting member for vertical movements and for pivotal movements about a vertical axis, an arm rigidly connected to the head and adapted to extend over the table and a platen carried by said arm adapted to rest upon the sand in a 95 flask.

4. In sand mold forming apparatus, the combination with a flask supporting table having means associated therewith for imparting percussive impulses thereto, of a follower above the table engageable with the sand in a flask, means for lifting the follower, and means for guiding the follower vertically, said guiding means permitting lateral movements of the follower after it has been elevated a predetermined amount.

5. In a sand mold forming apparatus, the combination with a flask supporting table having means associated therewith for imparting percussive impulses thereto, of a gravity actuated follower above the table including a platen adapted to rest on the sand in a flask and mounted for movement toward and from the table and for lateral movement to a position clear of the mold, means for lifting the follower to a position clear of a flask, and means for preventing lateral movements of the follower while in mold engaging positions and for retaining the follower in elevated position after the same has been moved laterally.

6. In sand mold forming apparatus, the combination with a flask supporting table having means associated therewith for imparting percussive impulses thereto, of a vertically movable gravity actuated follower comprising a head mounted for vertical movement at one side of the table, an arm carried by the head and extending over the table and a platen carried by said arm.

7. In sand mold forming apparatus, the combination with a flask supporting table having means associated therewith for imparting percussive impulses thereto, of a vertically movable gravity actuated follower comprising a head mounted for vertical movement at one side of the table, an arm rigidly connected to the head and extending over the table, a platen carried by the arm, and means for lifting the follower to raise the platen clear of a flask on the table.

8. In a device of the character described, the combination with a table, of a vertically disposed cylindrical guide member at one side of the table, a follower having a platen adapted to be positioned over the table and a supporting head provided with a hollow cylindrical portion slidably and rotatably mounted upon the guide member, said cylindrical portion of the head having a closed upper end and forming with said guide member a pressure chamber, and means for admitting fluid under pressure to said chamber to lift the platen.

9. In a device of the character described, the combination with a table, of a vertically disposed cylindrical guide member at one side of the table, a follower comprising a head slidably and rotatably mounted on said guide member, an arm rigidly connected to said head and adapted to extend over the table, a platen carried by said arm, and auxiliary guide members for preventing pivotal movement of the head during downward movement thereof.

10. In a device of the character described, the combination with a table, of a vertically disposed cylindrical guide member at one side of the table, a follower comprising a head slidably and rotatably mounted on said guide member, an arm rigidly connected to said head and adapted to extend over the table, a platen carried by said arm, a vertical guide pin at one side of said cylindrical guide member, and an annular plate fixed to the head and concentric with the cylindrical guide member, said plate having an opening in which said guide pin has a sliding fit.

11. In sand mold forming apparatus, the combination with a flask supporting table having means associated therewith for imparting percussive impulses thereto, of vertically movable pins adapted to be moved upwardly through openings in the table to engage and lift a flask off the table, and means for simultaneously operating said pins.

12. In sand mold forming apparatus, the combination with a flask supporting table having means associated therewith for imparting percussive impulses thereto, of a fluid pressure cylinder having a vertically movable part, a rigid frame fixed to said vertically movable part, and vertical pins fixed to said frame and movable through

openings in the table to lift a flask off the table.

13. In sand mold forming apparatus, the combination with a flask supporting table having means associated therewith for imparting percussive impulses thereto, of a fluid pressure cylinder having a vertically movable part, means for supplying fluid under pressure to said cylinder, means for limiting the upward movement of said movable part, a rigid frame fixed to the movable part and vertical lifting pins fixed to said frame and movable through openings in the table to lift a flask off the table.

14. In sand mold forming apparatus, the combination with a flask supporting table having means associated therewith for imparting percussive impulses thereto, of a gravity follower adapted to rest upon the sand in a flask, means for lifting the follower clear of the flask, and means for lifting and supporting a flask clear of the table.

15. In sand mold forming apparatus, a flask supporting table, a fluid pressure operated vibrator cylinder beneath the table centrally thereof for imparting percussive impulses thereto, a fluid pressure cylinder at one side of the table having a vertically movable pressure actuated part, a rigid frame carried by said movable part, said frame having arms straddling said vibrator cylinder, and vertical pins carried by said arms and adapted to be raised through openings in the table to lift a flask off the table.

16. In sand molding forming apparatus, a flask supporting table, means for imparting percussive impulses to the table comprising a vertically disposed fluid pressure operated vibrator cylinder beneath the table at the center thereof, and means for lifting the flasks off the table, comprising a frame arranged beneath the table and having side members straddling said cylinder, spaced vertical pins carried by each side member of the frame and slideable in openings in the table, and means for raising and lowering said frame.

17. In sand mold forming apparatus, a flask supporting table, means for imparting percussive impulses to the table comprising a vertically disposed fluid pressure operated vibrator cylinder beneath the table at the center thereof, and means for lifting flasks off the table comprising a frame having side members straddling said cylinder, vertical lift pins secured to each of said side members and movable through openings in the table, vertical guide members associated with said frame, and fluid pressure operated means for lifting said frame.

18. In sand mold forming apparatus, a flask supporting table, means for imparting percussive impulses to the table comprising

a vertically disposed fluid pressure operated vibrator cylinder beneath the table at the center thereof, a vertically disposed fluid pressure cylinder at one side of the table, 5 said cylinder having an inner fixed member, and an outer movable member having a skirt portion which has a sliding fit upon said inner member and means for admitting pressure to the cylinder to lift said outer 10 member, a rigid U-shaped frame having its base portion secured to said outer member and its arms straddling said vibrator cylinder, and spaced vertical lift pins fixed to each of said arms and adapted to be projected through openings in the table to lift a 15 flask off the table.

In testimony whereof, I hereunto affix my signature.

JOHN T. STONEY.
